United States Patent Office

Des. 221,579
Patented Aug. 24, 1971

221,579

WATCH BRACELET OR SIMILAR ARTICLE

Yuen Sang Poon, 36 Kam Wah St., Hong Kong

Filed Apr. 24, 1970, Ser. No. 22,624

Term of patent 14 years

Int. Cl. D11—01

U.S. Cl. D45—4

FIG. 1.

FIG. 2.

FIG. 3.

FIG. 4.

FIG. 5.

FIG. 6.

FIG. 7.

FIG. 8.

FIG. 9.

FIG. 1 is a top plan view of a watch bracelet showing my new design;

FIG. 2 is an enlarged top plan view of an end link unit.

FIG. 3 is a front elevational view of the link shown in FIG. 2;

FIG. 4 is an end elevational view of the link shown in FIG. 2;

FIG. 5 is a perspective view thereof;

FIG. 6 is an enlarged top plan view of a center link unit;

FIG. 7 is a front elevational view thereof;

FIG. 8 is an end elevational view thereof; and

FIG. 9 is a perspective view thereof.

I claim:

The ornamental design for a watch bracelet or similar article, substantially as shown.
